METALLIC FENCE CONSTRUCTION

Lester L. Rochester, Port Clinton, Ohio

Application November 15, 1949, Serial No. 127,449

3 Claims. (Cl. 256—21)

1

This invention relates to fences of the picket type, and particularly to the construction of the fence pickets, the supporting rails therefor, and the manner of attaching one to the other.

The primary object of the invention is the provision of a fence of this type having stamped metallic pickets and supporting rails therefor of strong and novel construction and with said parts secured together in a simple, efficient and improved manner whereby to enhance the practicability and commercial value of the fence.

Another object of the invention is the provision of a novel capping means for the picket which may take the form of an individual cap for each picket or a rail-type cap for all of the pickets of a fence.

Other objects and advantages of the invention will be apparent from the following detailed description, and from the accompanying drawings illustrating one embodiment thereof, and in which

Fig. 1 is a perspective view of a fragmentary portion of a fence embodying the invention, with some of the pickets attached to the rails and with the pickets shown as having individual capping members; Fig. 2 is a perspective view of a fragmentary portion of a fence embodying the invention, with the pickets equipped with a rail-type cap; Fig. 3 is an enlarged section on the line 3—3 in Fig. 1; Fig. 4 is a fragmentary section on the line 4—4 in Fig. 1, with the parts shown in perspective; Fig. 5 is an enlarged perspective view of a clamping plate used for clamping a picket and rail together; Fig. 6 is a fragmentary rear elevation of a picket with a clamping member in position therein; Fig. 7 is an enlarged perspective view of the upper end portion of a picket with the associated cap member raised therefrom; Fig. 8 is a section on the line 8—8 in Fig. 7; Fig. 9 is a perspective view of an individual cap member for a picket partially formed and with parts broken away, and Fig. 10 is an edge elevation thereof.

Referring to the drawings, 1 designates the posts of a fence, 2 the upper and lower rails connecting the posts and 3 the pickets attached to the rails. The rails 2 are stamped, rolled, or otherwise suitably formed from a heavy grade of sheet metal and are U-shape in cross-section with their edges preferably rolled back upon themselves. The bottoms or cross-portions of the channels of these rails are preferably corrugated or formed on their outer sides with longitudinally extending ridges, as shown at 4 in Figs. 1, 2 and 4, to provide a roughened surface against which

2

the pickets 3 are clamped. While the rail ends may be attached in any suitable manner to the posts 1, they are shown, in the present instance, as being supported by brackets 5 projecting from the posts and fixed to said brackets by bolts 6.

The pickets 3 are also stamped from sheet metal, or otherwise suitably formed, and each is of channel form, or U-shaped in cross-section, with its legs or opposing side wall portions 7 (Figs. 10 3 and 7) of shallow form and terminating in angular flanges 8 which project a short distance crosswise of the picket toward each other and then inwardly toward the face portion 9 of the picket. The free inturned edges of the flanges 8 terminate short of the face portion 9 and each of such flanges cooperates with the respective side edge portion 7 to form an edge channel 10 facing the front side of the picket. The rearwardly facing portions of the flanges 8 seat 15 against the front or corrugated sides of the rails 2 to which attached and preferably have cross ridges or corrugations which interengage with the rail corrugations to hold the pickets against movements transversely of the rails when clamped thereto. The front side portion 9 of each picket 20 is preferably formed with a central longitudinally extending ridge 11 which is of shallow form and slopes outwardly in both directions toward the respective side edges of the picket so as to give the picket strength and also to give it a pleasing 25 appearance.

The means for holding each picket to a rail comprises a clamping plate 14 (Figs. 3, 5 and 6) that extends crosswise of the picket within its 30 body channel and between the inturned portions of the flanges 8 and the front side 9 of the picket and is provided at each end with a rearwardly projecting flange 15 that projects into the respective edge channel 10 and bears outwardly at its free edge against the bottom of such channel, as best shown in Fig. 3. This clamp may be moved freely longitudinally of a picket to place it in register with a respective rail 2. A bolt shank 16 projects rearwardly from the plate 14 centrally thereof through a registering opening 17 in the web of the rail, and this receives a nut 18 for clamping the plate 14 and its picket to the rail. In this manner, the corrugated edges of each picket may be securely clamped against movement to the corrugated web of the rail.

Each picket is preferably finished at its top end with a cap 20 which in front view may be of any desired configuration. In the present instance, the cap 20 is of U or channel form in cross-section to adapt it to fit over the upper edge portion

of a picket. The cap member is formed by bending the side edge portions 21 thereof rearward and the top edge if of slanting or straight form, as in the present instance, is also formed by bending the top edge part 22 rearward. The top edge flange 22, which is thus formed, has its ends extended beyond the ends of the flange to form tongues 23 and 24 at the ends thereof and these tongues are bent down at the outer sides of the side edge flange portions 21 and fixed thereto by electric welding, or in any other suitable manner. In Figs. 9 and 10 the tongues 23 and 24 are shown as provided at their free ends with spurs 25 and 26, respectively, which are bent at right angles to the tongues and inserted through registering openings 27 in the respective side flanges 21 of the cap. These spurs may then be bent against the inner side of said flanges to prevent withdrawal thereof from the opening. When a cap member has been fitted over a picket end inlapping relation thereto, it is rigidly secured in position by bolts or screws inserted through registering openings 28 in the respective side edge flanges of the picket and cap member, or the parts may be electric welded or secured together in any other suitable manner.

The cap members 28 may be of any suitable configuration and may have their top edges either slanting crosswise of the picket, rounded, or of any other suitable form. The lower edge of the cap member may also be of any suitable or desired configuration, and in the present instance such edge is shown as of scalloped form, as indicated at 30 in Fig. 7. The picket may also have a surface ridge 31 projecting from its front side corresponding in shape to the lower edge of the cap member and serving as a stop for limiting the desired movement of the cap member on the picket, and also as a finish for the edge 30 of the cap member. The front ridge 11 of a picket may be tapered to a straight edge at the upper end of the picket, and in order to adapt the cap member to fit flush over such end portion of the picket, the front of the cap member may be formed with a corresponding tapered front bulge or ridge, as indicated at 32.

In Fig. 2 the cap member for the pickets is shown as of rail form and comprises a rail of channel form with the space between its legs narrowed to a width suitable for fitting closely over the tops of the pickets 3 and secured thereto by screws or bolts 35. The front leg of the rail may have shallow V bulges 36 which receive tapered upper end portions of the front picket ridges 11.

It is apparent that I have provided a simple, strong and durable fence of pleasing appearance, the rails and pickets of which are formed preferably by being stamped from sheet metal and with both members of channel form and secured together by interengaging clamping parts. Also that the pickets may have their top ends finished by cap members of any suitable configuration which are separate from the body por-

tions of the pickets and may comprise either individual cap members attached to the pickets or cap members of rail form extending over and forming a cap for a series of pickets.

I wish it understood that my invention is not limited to any specific construction, arrangement or form of the parts, as it is capable of numerous modifications and changes without departing from the spirit of the claims.

Having thus described my invention, what I claim as new, and desire to secure by United States Letters Patent, is:

1. In a fence having a rail and a metallic picket secured thereto, said picket being of channel form in cross-section with its side legs terminating in angular flanges which extend inwardly toward each other and then forwardly in the rail channel short of the web portion thereof, a clamping member extending crosswise within the picket channel and having legs extending rearwardly into the channels formed by the edge flanges of the picket and engaging the inturned portions of the flanges in opposition to the rail, and means projecting from the clamping member and engaging with the rail to hold the rail and picket in assembled relation.

2. In a fence construction, metallic rails of channel form with their channels facing rearwardly, a metallic picket of U-form in cross-section having its legs bearing against the web of the rails and terminating in angular flanges forming forwardly facing channels interiorly of the picket channel adjacent to each side edge thereof, means for anchoring the picket to the rails and comprising cross members of U-form disposed within the picket channel and having their legs projecting rearwardly into the side edge channels of the picket, and bolt means for attaching said cross members to the webs of the rails.

3. An arrangement as called for in claim 2, wherein the coacting surfaces of the picket and rails are corrugated in mating relation to resist longitudinal movements of the picket transversely of the rails.

LESTER L. ROCHESTER.
